UNITED STATES PATENT OFFICE.

FRANK J. McCANDLESS, OF ALLERTON, IOWA.

STARTER FOR INTERNAL-COMBUSTION ENGINES.

1,419,461.

Specification of Letters Patent. Patented June 13, 1922.

Application filed July 26, 1919. Serial No. 313,643.

To all whom it may concern:

Be it known that I, FRANK J. McCANDLESS, a citizen of the United States, and a resident of Allerton, in the county of Wayne and State of Iowa, have invented a certain new and useful Starter for Internal-Combustion Engines, of which the following is a specification.

The object of my invention is to provide an engine starting device of simple, durable and inexpensive construction, designed for use particularly in cranking or turning over the engine of an automobile or other motor vehicle, and including mechanism, whereby the weight of the operator may be used in itself or in combination with the principal muscles of the arms and back and lower limbs.

More particularly it is my object to provide in connection with an engine, a movable platform or the like upon which the operator can stand, said platform having suitable means for connecting it with the crank shaft of the engine, and a hand lever or levers for holding the operator steady on the platform, and for assisting in operating the platform for cranking the engine by means of the movement of the platform.

With these and other objects in view my invention consists in the construction, arrangement and combination of the various parts of the device, whereby the objects contemplated are attained, as hereinafter more fully set forth, pointed out in my claims and illustrated in the accompanying drawings, in which:

Figure 1 shows a side elevation of a portion of an automobile frame having an engine mounted thereon equipped with a starting device embodying my invention.

Figure 2 shows a top or plan view of my device.

Figure 3 shows a vertical sectional view of the device, taken on the line 3-3 of Figure 2, and illustrating part of the engine in side elevation.

Figure 4 shows a detail, sectional view taken on the line 4-4 of Figure 2.

Figure 5 shows a detail, sectional view taken on the line 5-5 of Figure 4.

Figure 6 shows a detail view of part of the starter mechanism.

Figure 7 shows a side elevation of a modified form of my device in one position of its movement.

Figure 8 shows a side elevation of the de-

vice shown in Figure 7 in another position of its movement.

Figure 9 shows a top or plan view of the same; and

Figure 10 shows a detail, sectional view of a portion of the device shown in Figures 7, 8, and 9.

In the accompanying drawings I have used the reference numeral 10 to indicate generally the frame of an automobile upon which is supported the engine 11 shown by dotted lines in Figure 2 under the hood 12. The engine 11 has a forwardly extending crank shaft 13 on which is loosely mounted the pinion 14.

In the form of the invention shown in Figures 1 and 6 inclusive, there is fixed to the shaft 13 adjacent to the pinion 14 a ratchet 15. Pivoted to the pinion 14 is a spring actuated pawl 16.

Pivoted at their rear ends on the side frame members of the automobile are forwardly extending levers 17 which are connected at their forward ends in front of the radiator 18 by means of a platform 19.

Suitably supported is a transverse shaft 20 arranged substantially forwardly of the pivot ends of the levers 17. The shaft has at its ends forwardly extending arms 21 at the forward ends of which are pins or the like 32 which extend through and travel in elongated slots 33 in the respective levers 17.

Mounted on the frame of the machine on the opposite sides thereof are supports or brackets 34. Pivoted to the upper end of each upright 34 is a lever 35. Each lever is pivoted near its end and extends forwardly as illustrated in Figures 1 and 2.

Pivoted to each lever arm 21 near its forward end is a link 36 which extends upwardly in the device and is pivoted to the rearward end of one of the levers 35.

The handles of the levers 35 normally stand in such positions that they may be readily and easily grasped by an operator standing on the platform 19.

Fastened between the two levers 17 is a transverse bar 36^a. Secured to the cross bar 36^a is an upwardly extending rack bar 37 arranged in mesh with the pinion 14.

A spring 38 may be employed for normally holding the levers 17 in their raised position.

In the practical operation of the device just described, it will be understood that when it is desired to crank the engine the

operator steps upon the platform 19 and grasps the handles of the lever 35, by which the operator will force the platform 19 downwardly for rotating the crank shaft and 5 thereby turn over the engine.

During the operation of the rack bar 37 on the pinion 14, the pawl 16 will engage the ratchet 15. If the compression of the engine is great, or if for any other reason 10 the weight of the operator is not sufficient for cranking the engine, it is obvious that the operator can also utilize his muscular strength by pulling upwardly on the levers 35. Thus it is obvious that the levers 35 15 serve a two-fold function. They assist the operator in steadyng himself and holding himself firm on the platform 19 and for enabling him to use his strength in cranking the engine.

20 The handles 35 may also be used for returning the platform to its upper position which can be done if desired while the operator is still standing on it, where it is necessary to operate the platform several times in 25 order to start the engine.

Ordinarily when the operator steps off the platform the spring 39 will return it to normal position.

In Figures 7 to 10 inclusive I have shown 30 a modified form of my invention.

In the form of the device shown in the figures just mentioned I have shown on opposite sides of the frame of the motor vehicle the brackets 40. Pivoted to the 35 brackets 40 are a pair of parallel spaced links 41 extending forwardly and pivoted at their forward ends to upright members 42. The upright members 42 support a rearwardly extending platform 43. Suitably 40 supported above the brackets 40 are brackets 44. Pivoted between its ends to each bracket 44 is a bell crank lever 45 having a relatively long handle, and having its free end pivoted to a downwardly extending link 46. 45 The lower end of each link 46 is pivoted to one of the links 41 between its ends.

Loosely mounted on the shaft 13 is a hollow drum 47. Fixed on the shaft 13 adjacent to the drum 47 is a disc 48 having an 50 internally toothed annular, peripheral flange 49. Pivoted to one end of the drum 47 is a spring actuated pawl 50 designed to coact with the ratchet formed by the disc 48.

Secured to one end of the drum 47 is a coil 55 spring 51, and the other end of which is connected with the frame of the machine.

Wound on the drum 47 is a cable 52, one end of which is connected to the rearward end of the platform 43.

60 Ordinarily the tension of the spring 51 keeps the cable wound up on the drum, and keeps the platform 43 in its raised position.

When, however, the operator steps upon the platform 43 and grasps the handles of 65 the lever 45, the weight of the operator as-

sisted by the application of his strength to the levers 45 lowers the platform 43 with a quick movement for turning over the engine.

At the same time the spring 51 is unwound. After the platform 43 has been 70 lowered, and when it is released, the spring 51 may wind up the drum 47 for winding the cable 52 thereon and returning the platform 43 to its normal position. The operation may be repeated as often as desired. 75

The advantages of such a structure as that herein shown are largely seen from the foregoing description. It will be seen that the weight of the operator can be used for turning over the engine with practically as much 80 speed and convenience as the ordinary crank can be operated, and with much less effort and strength.

The parts may be so constructed that they do not interfere with the ordinary operation 85 of the engine and do not interfere with the ordinary cleaning, oil supply, or with the repair work.

The parts are of very simple and inexpensive construction and a starter of this 90 kind can be manufactured at a low cost.

With a device of this kind the weight of the body, as well as the powerful muscles of the back, legs and arms may be used in operating the starter. 95

The rigid connection of the arms 21 with the shaft 20 holds the forward ends of the levers 17, and consequently the platform 19, level from side to side.

Some changes may be made in the construction, and arrangement of the parts of my improved starting device without departing from the essential features and purposes of my invention, and it is my intention to cover by my claims any modified forms of 100 structure or use of mechanical equivalents which may be reasonably included within their scope.

I claim as my invention:

1. The combination of a frame and a shaft 110 mounted therein with a platform pivoted on said frame and adapted to support a person standing on the platform, means for operatively connecting said platform with said shaft, and a hand lever operatively connected 115 with said shaft and adapted to be grasped by the person standing on the platform.

2. In a device of the class described, the combination of an internal combustion engine having a crank shaft, with a starter including a platform mounted for up and down movement, means for operatively connecting said platform with the crank shaft, and a lever operatively connected with said platform, the parts being so arranged that an 125 operator may stand on the platform and use his weight in moving the platform in one direction, and may grasp said lever for using his strength for moving the platform in either direction. 130

3. In a device of the class described; a platform; means for supporting said platform for swinging movement; means for operatively connecting said platform with an engine shaft; a lever fulcrumed between its ends; and means for operatively connecting said lever with said platform.
4. In a device of the class described; the combination of an internal combustion engine having a crank shaft; with mechanism adapted to be actuated by applying the weight of the body thereto for imparting rotation to said shaft; and means adapted to be simultaneously operated for acting upon said means for increasing its efficiency and for returning said first means to operative position.
5. In a starter for internal combustion engines a platform mounted for up and down movement, and means for operatively connecting said platform with an engine shaft, whereby movement of the platform in one direction imparts rotation to said shaft, while movement in the other direction does not effect rotation of the engine shaft, said platform being so constructed that the operator may stand on the platform with both feet, and support his entire weight thereon.
6. The combination of a frame, an engine mounted thereon, having a shaft, a platform mounted for up and down movement, means for operatively connecting said shaft with said platform, whereby the downward movement of the platform imparts rotation to said shaft, said means being constructed to permit the shaft to rotate at an accelerated speed without correspondingly affecting the platform, said platform being such that the operator can stand on it with both feet for utilizing his entire weight in moving the platform for rotating said shaft, and a handle device adapted to be grasped by the operator while standing on the platform, said handle device being operatively connected with said platform so that the operator may pull upwardly on the handle device for using the strength of his arms to assist his weight in lowering the platform and the operator may support his weight on the handle device for raising the platform.
7. The combination of a frame, an engine mounted thereon, having a shaft, a platform mounted for up and down movement, means for operatively connecting said shaft with
- said platform, whereby the downward movement of the platform imparts rotation to said shaft, said means being constructed to permit the shaft to rotate at an accelerated speed without correspondingly affecting the platform, said platform being such that the operator can stand on it with both feet for utilizing his entire weight in moving the platform for rotating said shaft, and a handle device adapted to be grasped by the operator while standing on the platform, said handle device being movable and operatively connected with said platform whereby the operator may use the strength of his arms in addition to his weight for operating the platform.
8. The combination of a frame, an engine mounted thereon, having a shaft, a platform mounted for up and down movement, means for operatively connecting said shaft with said platform, whereby the downward movement of the platform imparts rotation to said shaft, said means being constructed to permit the shaft to rotate at an accelerated speed without correspondingly affecting the platform, said platform being such that the operator can stand on it with both feet for utilizing his entire weight in moving the platform for rotating said shaft, and a handle device adapted to be grasped by the operator while standing on the platform, said handle device being operatively connected with said platform so that the operator may pull upwardly on the handle device for using the strength of his arms to assist his weight in lowering the platform and the operator may support his weight on the handle device for raising the platform.
9. In a device of the class described, a platform on which an operator may stand, means for supporting said platform for up and down movement, means for operatively connecting said platform with an engine shaft, and a handle device operatively connected with said platform.

Des Moines, Iowa, July 17, 1919.
FRANK J. McCANDLESS.
